UNITED STATES PATENT OFFICE

PAUL H. HORWITT, OF SPRINGFIELD, MASSACHUSETTS, ASSIGNOR TO THE MENASHA PRODUCTS COMPANY, OF CHICAGO, ILLINOIS, A CORPORATION OF WISCONSIN

DISPENSER

Application filed May 26, 1930. Serial No. 455,577.

This invention relates to a dispenser for folded articles, such as paper napkins and the like. More particularly, the invention relates to the actuating mechanism associated with the follower plate for advancing the folded articles to be dispensed toward the dispensing window.

One of the principal difficulties in connection with the operation of dispensers for folded napkins and the like has heretofore been the tendency of the dispensing mechanism either to hold the stack of folded napkins under too great compression to enable the napkins to be withdrawn easily or else under insufficient compression to maintain the napkins in the desired position relative to the dispensing window. Where the napkins in the dispenser are stacked vertically upon edge, the pressure of the follower plate 10 against the rear of the stack must be sufficient to maintain the napkins in erect position without permitting them to slump or crumple up. To accomplish this end, the follower plate not only must exert a fairly uniform pressure against the rear of the stack 15 of napkins in the dispenser but the pressure must be substantially uniform throughout the entire area of the napkin in order to prevent it from binding at the sides, top or bottom.

The present invention constitutes an improvement in this respect over the dispensing device disclosed in my copending application entitled "Dispenser", Serial No. 421,336, filed 20 January 17, 1930.

It is accordingly an object of this invention to provide a dispenser having improved actuating mechanism for maintaining the articles to be dispensed in proper position. 25 Other and further important objects of this invention will become apparent from the following description and appended claims.

On the drawing:

Figure 1 is a front elevational view of a 30 dispenser of my invention illustrating a suitable manner in which it may be mounted.

Figure 2 is an enlarged sectional view taken substantially on line II-II of Figure 1.

Figure 3 is a sectional view taken substan-

tially on line III-III of Figure 2, showing operation of actuating mechanism in dotted lines.

Figure 4 is a sectional view taken substantially on line IV-IV of Figure 2.

Figure 5 is a sectional view taken substantially on the broken line V-V of Figure 2, showing operation of actuating mechanism in dotted lines.

As shown on the drawing:

The reference numeral 1 indicates as a whole a dispenser of my invention, which may be suitably mounted, as shown in Figure 1, in guides 2 from the under side of a table top 3, or the like. The particular manner of mounting the dispenser, however, does not form a part of the present invention but is separately described and claimed in a copending application filed of even date here- 60 with, Serial No. 455,578.

The dispenser 1 comprises a casing 4, a drawer 5 slidably mounted therein and actuating mechanism, indicated as a whole by the reference numeral 6. The casing 4, which is of rectangular cross section and open at the front and top, is preferably formed of sheet metal, one piece being stamped to form the bottom and side walls 7, 8 and 9, respectively, of the body of the casing and another piece being flanged and secured to said body portion to form the rear wall 10. The side walls 8 and 9 for a portion of the length of their respective upper edges are extended inwardly and reversely bent to provide outwardly opening grooves 11 and 12 for receiving the inturned flanged ends of the guides 2. A gravity catch 13, pivoted from one of the guides 2 and normally engaged in a slot formed in the walls of the groove 12, serves to lock the casing in position upon the guides 2.

The drawer 5, which is in the form of a scoop open at the top and rear end, is likewise preferably formed of sheet metal and comprises a body portion formed from a single sheet stamped to provide a bottom wall 14 and side walls 15 and 16, respectively. A plate 18 is suitably secured to the front edges of the body portion of the drawer. Said plate 18 extends beyond the side, top and bot-

tom walls of the drawer to serve, when the drawer is in place within the casing, as a closure for the front end of the casing. Said plate 18 is provided with a suitably shaped 5 dispensing window 19 through which articles 200 may be singly removed. The drawer 5 is normally retained within the casing 4 by means of cooperating locking members 20 and 21 but may, upon releasing these locking 10 members from engagement with each other, be removed for refilling with napkins or the like.

The dispensing mechanism 6 comprises a pair of jointed levers 22 and 23, pivotally connected as at 24 and 25, respectively, to angle pieces 26 and 27 secured to the rear wall 10 of the casing. At their respective front ends, the jointed levers 22 and 23 are pivotally connected by means of angle pieces as at 28 and 29 to a follower plate 30. Said follower plate 30 is of substantially the same area as the cross sectional area of the inside of the drawer 5 and is supported by means of the jointed levers 22 and 23 in a constantly upright position, as will be more clearly explained later on. A roller 31 is mounted from the rear face of the follower plate 30 by means of bracket members 32. Said roller 31 serves to eliminate friction that would otherwise exist between the bottom edge of the follower plate 30 and the bottom of the drawer 5 and facilitates the movement of the follower plate within the dispenser.

The jointed lever 22 is secured at its ends, 35 as at 28 and 24, to upper corner portions of the follower plate 30 and rear end wall 10, respectively, whereas the other jointed lever 23 is connected to lower diametrically opposed corner portions of the follower plate 30 and 40 rear wall 10. Accordingly, the jointed lever 22 is bent downwardly and the lever 23 is bent upwardly to permit said levers in full bent position, as shown in dotted lines, to be accommodated within said casing. This arrangement also results in a compensating action, as will later be explained.

The links of the jointed lever 22 are pivotally connected at their adjacent ends by means of a pin 33, upon which is mounted a 50 coiled spring 34. The ends of the spring 34 extend in opposite directions along the links forming the jointed lever 22 and are bent as at 35 and 36, respectively, for reception in notches 37 and 38 formed in the upper edges 55 of said links. The coiled spring 34 being under compression tends to uncoil and in so doing to straighten out the lever 22. One of the links of the lever 22 is extended beyond the pivot pin 33 with its end bent inwardly to provide a stop 17 for engagement with the lower edge of the other link.

In a similar manner the links of the jointed lever 23 are pivotally connected at their adjacent ends as at 40 and a coiled spring 41 provided. The ends of said spring 41 are bent

in, as at 42 and 43 to extend through notches 44 and 45 formed in the lower edges of the links. One of said links of the lever 23 extends beyond the pivot pin 40 and is turned inwardly, as at 46, to provide a stop for engagement with the upper edge of the other link to limit the spreading action of the spring. Movement of the jointed levers 22 and 23 is indicated by the dotted lines in Figures 3 and 5.

Assuming that the dispenser is empty, the drawer 5 is unlocked by inserting a finger through the dispensing window 19 and lifting up the catch 21 from its engagement with the catch member 20. The drawer is then pulled forwardly for complete removal from the casing. After being filled with folded paper napkins 200, the drawer is replaced in the casing. While the drawer is out, the jointed levers 22 and 23 not only support the follower plate 30 but prevent it from advancing beyond the front edge of the casing, due to the stops 17 and 46 provided for this purpose. In the act of replacing the drawer, the follower plate 30 will be pushed backwardly by the stack of napkins therein until it assumes a position such as that indicated in dotted lines in Figures 3 and 5. The extra compression thus placed upon the springs 34 and 41 will tend to spread apart the ends of the respective levers 22 and 23 and thus cause pressure acting through the follower plate 30 against the rear of the stack of napkins, tending to urge the stack toward the dispensing window. As the napkins are removed one by one and the stack diminishes in size, the continued action of the springs 34 and 41 maintains the requisite pressure between the follower plate and the stack of napkins to keep the napkins erect and in proper dispensing position.

It should be noted that the arrangement of the jointed levers 22 and 23 to act against the upper and lower portions of the follower plate 30, respectively, tends to equalize the pressure upon the top and bottom of the follower plate 30 so as to maintain it in a vertical plane at all times. If accidentally the follower plate becomes tipped at an angle, the compensating action of the spring actuated levers will promptly cause the follower plate to regain its proper position as soon as the accidental force causing the tipping is removed. The elimination of friction between the follower plate and the bottom wall of the drawer 5 by means of the roller 31 further aids in keeping the follower plate in correct position. It is thus practically impossible to cause the follower plate to bind against the walls of the drawer when filling the dispenser, as is frequently the case in other types of dispensers not embodying my improved, compensating mechanism for advancing the follower plate.

I am aware that many changes may be

made and numerous details of construction may be varied through a wide range without departing from the principles of this invention, and I, therefore, do not purpose limiting the patent granted hereon otherwise than necessitated by the prior art.

I claim as my invention:

1. A dispenser for folded paper napkins comprising a casing, a drawer slidable in said casing, a follower plate, spring-pressed lever means pivoted on the rear wall of said casing and also pivoted on said plate near diagonally opposite corners thereof, and a roller centrally positioned on said plate extending below the lower edge thereof.
2. A dispenser for paper napkins comprising a casing, a follower plate, a pair of spring-pressed pivotally connected levers having a pivotal connection with the rear wall of said casing and having a pivotal connection with said plate at near one corner of said plate, another pair of spring-pressed pivotally connected levers having a pivotal connection with the rear wall of said casing and having a pivotal connection with said plate at near a corner of said plate diagonally opposite to said first-mentioned plate connection, said levers being adapted to urge said plate forwardly towards the front end of said casing, means to limit the extent of forward movement of said plate and to simultaneously prevent movement of the levers of each of said pairs of levers into alined straight-line relation, said means comprising a stop member on one lever of a pair of levers adapted to engage the other lever of said pair of levers.
3. A dispenser for paper napkins comprising a casing open at its front end, a follower plate in said casing, an arm formed of a pair of pivotally connected members, said arm having a pivotal connection near a corner of said plate and a substantially alined pivotal connection with the rear wall of said casing, another similar arm having a pivotal connection near a diagonally opposite corner of said plate and a substantially alined pivoted connection with the rear wall of the casing, springs cooperable with said arms to urge said plate forward towards the front end of said casing, and means on said arms to limit the extent of forward movement of said plate and to simultaneously prevent straight-line alinement of the connected members of said arms.

In testimony whereof I have hereunto subscribed my name at New York, New York County, New York.

PAUL H. HORWITT.
